United States Patent Office

Des. 217,598
Patented May 19, 1970

217,598

INDUSTRIAL VEHICLE BODY

Rigsby C. Satterfield, Chalfont, Pa., assignor to Eaton
Yale & Towne Inc., Cleveland, Ohio, a corporation of
Ohio

Filed May 7, 1969, Ser. No. 17,051

Term of patent 14 years

Int. Cl. D12—09

U.S. Cl. D14—3

FIG. 1 is a perspective view of my new design for an industrial vehicle body;

FIG. 2 is a top plan view thereof;

FIG. 3 is a side elevational view thereof;

FIG. 4 is a rear elevational view thereof;

FIG. 5 is a further side elevational view of the industrial vehicle body of FIG. 1 illustrating further design features thereof.

The wheels, tires and fork lift units are shown in broken lines for illustrative purposes only.

I claim:

The ornamental design for an industrial vehicle body, as shown and described.
